UNITED STATES PATENT OFFICE.

THOMAS A. FOX, OF NEWARK, NEW JERSEY, ASSIGNOR TO THE STEFFENS-AMBERG CO.,
A CORPORATION OF NEW JERSEY.

HARNESS.

1,167,811.

Specification of Letters Patent.

Patented Jan. 11, 1916.

Application filed February 27, 1912. Serial No. 680,314.

To all whom it may concern:

Be it known that I, THOMAS A. Fox, a citizen of the United States, residing at Newark, in the county of Essex and State of New Jersey, have invented certain new and useful Improvements in Harness; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention has reference, generally, to improvements in harness; and, the present invention relates, more particularly, to a novel harness-attachment for the neck-pieces of breast-collars, and which harness-attachment is hereinafter termed as the ring-neck terret or ring-neck spider.

20 The invention has for its principal object to provide a novel, neat, and simply constructed ring-neck terret or ring-neck spider, the purpose of which is to collect the several short neck straps and cause them to set neatly upon the sides of the neck of the horse, and also to provide a device in the form of a ring-neck terret or ring-neck spider, for the reception of the driving reins, so as to prevent the reins from dropping below the said device and catching in other parts of the harness or about the ends of the shafts of the vehicle.

25 The invention consists, primarily, in the novel ring-neck terret or ring-neck spider hereinafter set forth; and, the invention consists, furthermore, in the novel combination and arrangements of the several devices and parts hereinafter more fully described and then finally embodied in the clause of the claim which is appended to and which forms an essential part of this specification.

30 The invention is clearly illustrated in the accompanying drawings, in which:

Figure 1 is a face view of the ring-neck terret or ring-neck spider and portions of the several short neck straps shown in their collected or assembled relation with the said ring-neck terret or ring-neck spider. Fig. 2 is a face view of the said ring-neck terret or ring-neck spider in its detached relation; Fig. 3 is a side elevation of the same, looking in the direction of the arrow α in said Fig. 2; and Fig. 4 is a longitudinal vertical sec-

tion of the device, said section being taken on line 4-4 in said Fig. 2, looking in the direction of the arrow y .

Similar characters of reference are employed in all of the above described views, 60 to indicate corresponding parts.

Referring now to the said drawings, the reference-character 1, indicates the upper main portion or neck-piece of a breast-collar and 2 and 3 represent the short members 65 forming the double or split hip-strap of the breast collar, all of which are collected and secured in their assembled relation by means of a ring-neck terret or ring-neck spider 4 made according to and embodying the principles of the present invention in the manner to be presently more fully set forth.

This ring-neck terret or ring-neck spider comprises a ring-shaped main body, as 5, which may be of any suitable cross-section, 75 preferably circular, and extending centrally across and upwardly from said ring-shaped body 5 is a suitably formed loop-shaped element 6, said element comprising two members, as 7 and 8, which are integrally connected with parts of the said ring-shaped body 5, and extend, preferably, in upward and slightly outwardly projecting directions, substantially as illustrated in Fig. 3 of the drawings, and are connected by means of 80 preferably upwardly curving connecting bar or member 9. The said members 7 and 8 are preferably of the configuration shown in the several figures of the drawings, and the cross-section of the connecting member 9 is preferably that represented in Fig. 4 of 85 the drawings. It will be understood, however, that the various shapes and conformations of these several parts may be varied and changed, without departing from the 90 scope of the present invention.

The manner of attaching the neck-piece 1 of the breast-collar and the double or split hip-strap to the ring-neck terret or ring-neck spider is clearly shown in Fig. 1 of the 100 drawings, the parts being permanently connected during the construction of the harness, so as to form part of the harness, the neck-piece being formed with an open portion, as 11, so that its ends, when passed around the ring-shaped body 5 will lie upon opposite sides of one of the outwardly extending members, as 7, of the element 6, and that the said bar 9, when the harness has 105 been placed upon the horse, is vertical or 110

substantially so. The two members 2 and 3 of the double or split hip-strap are permanently secured to the said ring-shaped body 5 on opposite sides of the other member, as 5 8, of the element 6, whereby a perfect and neat arrangement and connection of these permanently secured elements, comprising 1 part of the harness is the result.

The driving reins or lines 10 of the harness are readily passed between the ring-shaped body 5 and the loop-shaped element 6, as clearly illustrated in said Fig. 1 of the drawings.

I claim:—

15 A ring-neck terret or spider comprising a ring-shaped main body of circular configuration flat so that it will lie in a single straight plane, and an upwardly projecting loop-shaped element extending centrally and 20 transversely across said ring-shaped body

in a straight plane at right angles to the single straight plane of the said ring-shaped body, said loop-shaped element comprising a pair of upwardly extending end-members projecting at obtuse angles in outward directions oppositely from the outer marginal edge-portion of said ring-shaped body, and a curved connecting bar between the end-portions of said angularly disposed and upwardly and outwardly projecting 25 end-members, substantially as and for the purposes set forth.

In testimony, that I claim the invention set forth above I have hereunto set my hand this 24th day of February, 1912.

THOMAS A. FOX.
